To all whom it may concern:

Be it known that I, GUIDO GNÜCHTEL, manufacturer, a subject of the King of Saxony, residing at Lauter, Kingdom of Saxony, 5 German Empire, have invented and produced a new and original Design for Kitchen Vessels, of which the following is a specification.

My invention relates to a design for a kitchen utensil, and is illustrated in the accompanying drawings, wherein—

Figure 1 is a side elevation of the kitchen vessel of my design. Fig. 2 is a plan view of the same.

Like parts are indicated by the same letter in both figures.

¹⁵ *a* is the body of the kitchen vessel, outwardly bulging around the bottom, as indicated at *b*.

c is the top or upper opening.

The body of the utensil is so shaped that its smallest cross-section is at the top and its largest near the bottom, the outer section forming a line composed of two arcs of a circle, the upper one concave and the lower convex. ²⁰
